UNITED STATES PATENT OFFICE.

ARTHUR R. CASTAGNER, OF MINNEAPOLIS, MINNESOTA.

CARBURETER.

1,253,936.

Specification of Letters Patent. Patented Jan. 15, 1918.

Application filed March 18, 1916. Serial No. 85,122.

To all whom it may concern:

Be it known that I, ARTHUR R. CASTAGNER, a citizen of the United States, residing at Minneapolis, in the county of Hennepin 5 and State of Minnesota, have invented new and useful Improvements in Carbureters, of which the following is a specification.

This invention relates to carbureters and while especially designed for use in connection with engines of motorcycles, it will be evident as the description proceeds that the carbureter is useful also in connection with any internal combustion engine.

The object of the invention is to produce 15 a carbureter which is particularly economical in the consumption of fuel, which is especially adapted for quick acceleration and certain parts of which may be adjusted to suit the particular engine in connection with 20 which it is employed. A further object in view is to provide a carbureter having the characteristics above indicated, with a hot air manifold by means of which hot air may be supplied to the main and auxiliary air 25 intake openings of the carbureter.

One of the principal objects of the invention is to produce in connection with the main and auxiliary air intake openings and the mixture outlet opening, a throttle valve 30 of novel construction and arrangement and having a compound movement and also associated with the fuel regulating valve in such manner that the main and auxiliary air inlet openings and the mixture outlet 35 opening are simultaneously opened and closed and the fuel inlet valve shifted, in order that a proper mixture of air and hydrocarbon may be obtained under all adjustments of the throttle valve in accordance 40 with the demands of the engine.

With the above and other objects in view, the invention consists in the novel construction, combination and arrangement of parts, as herein described, illustrated and claimed.

50 In the accompanying drawings:—

Figure 1 is a diametrical section through a carbureter embodying the present invention.

Fig. 2 is a detail perspective view of the 55 throttle valve.

Fig. 3 is a similar view of the carbureting chamber and the fuel trap.

Fig. 4 is a detail view of the throttle actuating roller, and the adjusting means therefor.

55

Fig. 5 is a detail perspective view of the fuel nozzle.

Fig. 6 is a view partly in section and partly in elevation showing the heater which connects with the manifold controlling the 60 supply of air to the main and auxiliary air inlet openings of the carbureter.

The carbureter contemplated in this invention comprises the main body section or bowl 1 which incloses and forms the fuel 65 chamber 2 the same being normally closed at the top by means of a cap section 3. The central portion of the cap 3 is depressed to form a cup-shaped portion 4 lying within the fuel chamber 2 and also an internally 70 threaded neck 5 into which is screwed the upper threaded portion of a carbureting chamber 6 which gradually increases in size toward its lower end where it passes through a central opening 7 in the bottom of the 75 bowl or fuel chamber 2. The carbureting chamber 6 is formed at its lower end with a flange 8 which seats against the bottom of the bowl or fuel chamber 1 and forms a tight joint.

80

At its lower or receiving end, the carbureting chamber 6 is provided with a diametrically extending web 9 and a depending tubular nozzle extension 10. The bore of the extension 10 is extended through the 85 web 9 as shown in Fig. 1 and is internally threaded to receive a screw threaded plug 11 into which is screwed the lower end of a tubular jet or nozzle 12. The nozzle 12 extends upwardly within the carbureting 90 chamber 6 and has its upper end enlarged and of cylindrical formation as indicated at 13, said enlarged portion of the nozzle being formed in the underside thereof with air inlet ports 14. A fuel regulating valve 95 15 of the needle type is shown as co-operating with the discharge end of the nozzle 12 and controlled by means hereinafter described. Fuel inlet ducts 16 extend through the web 9 of the carbureting chamber 6 as 100 shown in Fig. 1 to permit the fuel to enter the extension 10. The lower end of the tubular extension 10 is threaded and passes through a main air tube or horn 17 where

it receives a clamping nut 18 that holds the tube or horn 17 tightly against the bottom of the bowl 1. A high speed fuel regulating valve 19, preferably of the needle type, is threaded through the nut 18 and provided with a milled head 20 or the equivalent thereof. The valve 19 cooperates with the receiving end of the nozzle 12 and regulates the amount of fuel which may 10 pass to the nozzle.

Connected directly to the cap 3 of the bowl 1 is a throttle valve chamber 21 the same being shown as provided with a flange 22 secured in any convenient manner to the 15 cap 3. The throttle valve chamber or casing 21 is provided at one side with a mixture outlet 23 and at a substantially diametrically opposite point with an auxiliary air inlet 24 in which is arranged an auxiliary 20 air regulating valve 25 shown as of the butterfly type. The top of the throttle valve chamber 21 is practically closed by an end wall 26 formed, however, with a central opening to receive the tubular stem 27 of a 25 hollow cylindrical or tubular throttle valve 28 which is illustrated in detail in Fig. 2. The throttle valve chamber is in the form of a hollow cylinder, as well as the throttle valve 28 and the latter is adapted to be oscillated by a throttle lever 29 fast on the tubular stem 27 of said throttle valve and arranged exteriorly of the valve casing. The throttle valve is formed in one side thereof with a mixture outlet opening 30 30 and about opposite said opening 30 is an auxiliary air inlet opening 31, the openings 30 and 31 adapted to respectively and simultaneously register with the mixture outlet port 23 and the auxiliary air inlet 24. 35 The throttle valve stem 27 is internally threaded to receive a threaded and longitudinally adjustable bushing 32 connected at its lower extremity to the valve 15 above referred to, the result of which is that when 40 the throttle valve 28 is moved lengthwise of the valve chamber 21, the fuel regulating valve 15 is correspondingly and quickly shifted. A tensioning spring 33 is mounted within the bushing 32 and bears at one end 45 against the adjacent end of the valve stem 15, permitting the fuel valve to move away from its seat as the suction of the engine increases. Bearing against the opposite end of the spring 33 is a tensioning screw 34 50 which is threaded into the outer end of the bushing 32 and is therefore adjustable exteriorly of the carburetor. 35 represents a jam nut for maintaining the adjustment between the bushing 32 and the tubular valve 55 stem 27. A coiled expansion spring 36 encircles the tubular valve stem 27 and exerts a pressure against the head of the throttle valve 28 to assist in returning the latter to its closed position.

The throttle valve 28 has the lower end 65 thereof contracted in size to form a frustoconical portion 37 formed with a number of air inlet ports 38 and is then further contracted to form a conical valve face 39 movable toward and away from a valve seat 70 40 formed at the junction between the upper extremity of the carbureting chamber 6 and the depressed central portion of the cap 3.

In order to effect a reciprocatory movement of the throttle valve simultaneously 75 with the oscillatory movement thereof, the throttle valve is provided with a cam way 41 which receives a roller 42 journaled on an oscillatory carrier 43 journaled in a bearing opening 44 in an offset portion of the 80 throttle valve casing 21. The carrier 43 is provided with an operating arm 45 having a handle 46 and a slotted segment 47 through which passes a headed pin or stud 48 on which is mounted a tension spring 49 which 85 bears against the segment 47 to hold the roller 42 in a certain fixed position while permitting said roller to be adjusted for the purpose of enabling the reciprocatory throw of the throttle valve to be adjusted and regulated. It will be apparent that as the 90 throttle valve is oscillated the roller 42 operating in the cam way 41 will cause a reciprocatory movement of the throttle valve thereby shifting the valve face 39 toward 95 and away from the valve seat 40 to accordingly increase or diminish the volume of air passing from the carbureting chamber 6 around the outside of the lower portion of the throttle valve. Any air passing by the 100 valve face 39 will be admitted through the ports 38 to the interior of the throttle valve.

50 represents the automatic cut-off valve which controls the fuel supply connection 51 leading to the carburetor, 52 represents the lever for operating the valve 50, and 53 represents the float in the fuel chamber 2 which is connected to the lever 52, the float 53 and the parts controlled thereby being of the usual construction and arrangement 105 found in many float feed carburetors.

In cold weather it is found desirable to employ a heater shown as embodying a hollow cylindrical jacket 54 the end walls 115 of which are formed with openings to receive the exhaust pipe 55 of the engine. The heater is provided with air inlet perforations 56 and with a hot air outlet neck 57 to which is connected a pipe 58 preferably of the flexible type, the same being connected at its discharge end to the threaded end portion 59 of a manifold 60 which is connected at 61 to the auxiliary air inlet 24 and connected at 62 to the main air inlet tube or horn 17.

From the foregoing description, taken in connection with the accompanying drawings, the operation of the carburetor will 125

now be understood. When the carbureter is throttled down and the engine is operating at low speed, the throttle valve is in its closed or nearly closed position, thereby closing the auxiliary air inlet and the mixture outlet and also preventing the main air supply from passing by the valve face 39. In this position also the fuel regulating valve 15 is almost closed. The air at this time is admitted through the main air tube or horn 17 and passes on opposite sides of the web 9 into the carbureting chamber 6, it being understood that suction in said chamber is produced by the operation of the piston or pistons of the engine and it being also understood that the port 30 is so designed as to afford the necessary communication between the interior of the valve and the intake pipe or manifold of the engine. By operating the throttle lever 29, the throttle valve 28 is oscillated or partially turned on its longitudinal axis thereby further opening the mixture outlet port of the valve and auxiliary air inlet port thereof. Simultaneously with this movement of the throttle valve, the valve face 39 is moved away from the valve seat 40 allowing additional air to pass from the carbureting chamber 6 through the ports 38 into the throttle valve. Also simultaneously with this movement of the throttle valve, the fuel regulating valve 15 is moved away from its seat in the nozzle 12 thereby admitting of the feed of a greater amount of fuel. As previously noted, the parts such as the throttle valve, the fuel regulating valve 15 and the butterfly regulating valve 25 are adjusted in accordance with the particular engine in connection with which the carbureter as a whole is used. The valve 19 is for the purpose of regulating what is known as the high speed adjustment, the valve 19 serving to regulate the quantity of fuel which is allowed to pass through the spray nozzle 12. A certain proportion of the air in the carbureting chamber 6 is drawn through the perforations or ports 14 in the spray nozzle taking up the fuel and carrying the same into the throttle valve 28. By adjusting the roller 42, the throw of the reciprocatory movement of the throttle valve may be regulated to suit conditions and requirements.

By reason of the construction described, the admixture of fuel and air may be adjusted and proportioned in such manner as to obtain the greatest efficiency and economy in accordance with the engine in connection with which the carbureter is used and furthermore, the carbureter as a whole is adapted for both summer and winter use and the entire mechanism thereof, after the carbureter has been adjusted, is controlled by the single throttle lever 29. Further-

more, the flow of fuel is smooth and constant owing to the large air channels and a reserve supply of fuel is continually available for acceleration purposes. 65

Having thus described my invention, I claim:—

1. In a carbureter, the combination of a carbureting chamber, a main air inlet at the bottom of said carbureting chamber, a throttle valve chamber above and in communication with said carbureting chamber and formed with laterally opposed auxiliary air inlet and mixture outlet openings, an oscillatory cylindrical throttle valve formed with auxiliary air inlet and mixture outlet openings adapted to register with the corresponding openings of the throttle valve chamber, said throttle valve having a reduced tubular portion thereof extended downwardly into the carbureting chamber, said tubular portion being of less diameter 80 than the mixing chamber to leave an annular air space between the extended portion of the throttle valve and the inner surface of the mixing chamber, a fuel nozzle discharging within said extended portion of 90 the throttle valve, and a fuel valve co-operating with said fuel nozzle and carried by said throttle valve. 95

2. In a carbureter, the combination of a carbureting chamber, a main air inlet at the bottom of said carbureting chamber, a throttle valve chamber above and in communication with said carbureting chamber and formed with laterally opposed auxiliary air inlet and mixture outlet openings, an oscillatory cylindrical throttle valve formed with auxiliary air inlet and mixture outlet openings adapted to register with the corresponding openings of the throttle valve chamber, said throttle valve having a tubular portion thereof extended into the carbureting chamber, a fuel nozzle discharging within said extended portion of the throttle valve, the upper end of said fuel nozzle being of enlarged tubular formation and lying 110 within the extended portion of the throttle valve, and a fuel valve co-operating with said fuel nozzle and carried by said throttle valve. 115

3. In a carbureter, the combination of a carbureting chamber, a main air inlet at the bottom of said carbureting chamber, a throttle valve chamber above and in communication with said carbureting chamber and formed with laterally opposed auxiliary air inlet and mixture outlet openings, an oscillatory cylindrical throttle valve formed with auxiliary air inlet and mixture outlet openings adapted to register with the corresponding openings of the throttle valve 120 chamber, said throttle valve having a tubular portion thereof extended into the carbureting chamber, a fuel nozzle discharging 125

- within said extended portion of the throttle valve, and a fuel valve coöperating with said fuel nozzle and flexibly carried by said throttle valve.
5. 4. In a carbureter, the combination of a carbureting chamber, a main air inlet at the bottom of said carbureting chamber, a throttle valve chamber above and in communication with said carbureting chamber and formed with laterally opposed auxiliary air inlet and mixture outlet openings, an oscillatory cylindrical throttle valve formed with auxiliary air inlet and mixture outlet openings adapted to register with the corresponding openings of the throttle valve chamber, said throttle valve having a tubular portion thereof extended into the carbureting chamber, a fuel nozzle discharging within said extended portion of the throttle valve, and a fuel valve coöperating with said fuel nozzle and carried by said throttle valve, said throttle valve being formed with a plurality of air inlet perforations located above the upper end of the fuel nozzle.
10. 5. In a carbureter, the combination of a carbureting chamber, a main air inlet at the bottom of said carbureting chamber, a throttle valve chamber above and in communication with said carbureting chamber and formed with laterally opposed auxiliary air inlet and mixture outlet openings, an oscillatory cylindrical throttle valve formed with auxiliary air inlet and mixture outlet openings adapted to register with the corresponding openings of the throttle valve chamber, said throttle valve having a tubular portion thereof extended into the carbureting chamber, a fuel nozzle discharging
- within said extended portion of the throttle valve, and a fuel valve coöperating with 40 said fuel nozzle and carried by said throttle valve, said auxiliary air inlet and mixture outlet openings being located above the discharge end of the fuel nozzle.
15. 6. In a carbureter, the combination of a carbureting chamber, a main air supply communicating with the bottom of said carbureting chamber, a throttle valve chamber above and in communication with said carbureting chamber, an auxiliary air supply in 45 communication with said throttle valve chamber, a hollow cylindrical and oscillatory throttle valve mounted in said throttle valve chamber and formed with auxiliary air inlet and mixture outlet openings, a 50 fuel nozzle having an enlarged tubular upper end formed with primary air inlet ports, a fuel valve coöperating with said nozzle and carried by said throttle valve, means for oscillating said throttle valve, and means 55 for imparting an up and down movement thereto, during the oscillatory movement thereof, said throttle valve having a reduced tubular lower end lying between and in spaced relation to the enlarged tubular upper part of the fuel nozzle and the wall of the carbureting chamber, the latter being formed with a valve seat, and the throttle valve having a valve face movable toward and away from said valve seat.
20. 7. In testimony whereof I affix my signature in presence of two witnesses.
